ELECTRIC TOASTER

Taylor Barnes, Shreveport, La.

Application July 20, 1950, Serial No. 11,272

Term of patent 14 years

(Cl. D81—10)

To all whom it may concern:

Be it known that I, Taylor Barnes, a citizen of the United States, and a resident of Shreveport, Caddo Parish, Louisiana, have invented a new, original, and ornamental Design for an Electric Toaster, of which the following is a specification, reference being had to the accompanying drawing, forming part thereof, in which:

The figure is a perspective view of an electric toaster embodying my new design. The two end portions are identical excepting for the operating elements shown on the right-hand side.

I claim:

The ornamental design for an electric toaster, as shown and described.

TAYLOR BARNES.
